UNITED STATES PATENT OFFICE.

BENJAMIN F. RINDFLEISCH, OF CLEVELAND, OHIO, ASSIGNOR, BY MESNE ASSIGNMENTS, TO THE NATIONAL-ACME COMPANY, OF CLEVELAND, OHIO, A CORPORATION OF OHIO.

COLLAPSIBLE TAP.

1,214,954.

Specification of Letters Patent. Patented Feb. 6, 1917.

Application filed March 25, 1916. Serial No. 86,562.

To all whom it may concern:

Be it known that I, BENJAMIN F. RINDFLEISCH, a citizen of the United States, residing at Cleveland, in the county of Cuyahoga and State of Ohio, have invented certain new and useful Improvements in Collapsible Taps, of which the following is a specification.

This invention relates to improvements in taps, and more particularly to that class thereof known as collapsible taps, the object of the invention being to provide a tap of this character which is adjustable to thread work of varying diameters, and in which the cutters or chasers will be automatically released from contact with the threads of the work after the tap has cut its required length, and which tap can be removed from the work without the necessity of reversing or backing out of the threaded piece.

A further object of the invention is the provision of a tap of the character specified in which the length of the tapping operation of which the tap is capable is not limited by the length of the chasers or cutting portions, but which may be used for tapping to a depth many times the length of the cutters and in places where it would be inconvenient or impossible to use the ordinary form of tap.

A further object of the invention is the provision of a tap of the character specified which may be used for right or left-hand threading without the necessity of changing the construction of the tap operating mechanism, and in which all the working parts thereof may be hardened and ground without materially increasing the cost of manufacture, and the cutter blades or chasers of which are extremely simple in construction and inexpensive to manufacture.

In the drawings accompanying and forming part of this specification, Figure 1 is a side view of my improved tap showing the same assembled for use, with the cutters or chasers in their advanced position; Fig. 2 is an end view of Fig. 1, looking in the direction of the arrows; Figs. 3, 4, 5 and 6 are sectional views taken respectively on the lines 3—3, 4—4, 5—5 and 6—6, Fig. 1, looking in the directions indicated by the arrows in Fig. 1; Fig. 7 is a sectional view

taken on line 7—7, Fig. 9; Fig. 8 is a perspective view of one of the chasers or cutters detached from the body of the tap; Fig. 9 is a side view similar to Fig. 1, but showing the cutters withdrawn; Fig. 10 is a longitudinal section of the tap as shown in Fig. 9; Fig. 11 is a longitudinal section of the tap with the chasers in advanced position as shown in Fig. 1; and Fig. 12 is a sectional view showing a modified form of core member or chaser adjusting means.

Similar characters of reference indicate corresponding parts in the different figures of the drawings.

I am aware there are a number of taps on the market that are known as collapsible taps, but in all of those forms with which I am familiar there are many disadvantages in the use thereof which it is the object of this improvement to overcome. For instance, with all other forms of taps with which I am familiar the depth that can be tapped is limited by the length of the chaser or cutter blade, for the reason that the mechanism for operating the tap is so bulky that the diameter of the body that houses such mechanism is much greater than the cutting size of the chasers, and therefore it is impossible to use them to cut or tap to any great depth or in the bottom of a deep hole of approximately the same diameter as the portion required to be threaded; whereas with the present improvement there is no limit of depth to which the work may be tapped, it being only necessary to increase the length of shank, which is in no way detrimental to the operation of the tap, since the chaser blades are supported throughout their entire length and operated by a center portion, and as the extreme diameter is the cutting size of the tap it is possible to use it in a great many places where it would be impossible to use other forms of taps.

In the form shown in the drawings, this improved tap comprises a body or head 2, in the front face of which are milled a plurality of radial slots 3 of the required depth and width to accommodate the chasers or cutter blades 4, four of which are shown herein, a disk or plate 5 being secured to the front face of the body 2 by means of screws or in any other suitable manner to retain the cutter blades within the slots 3.

Through the center of the body 2, lengthwise thereof, is bored a hole large enough to permit the passage therethrough of the shank portion 6 of a core member, the front 5 portion of which core member is formed with a plurality of flattened portions, as 7, four being shown in the present instance, one for each cutter blade, for the purpose hereinafter described, the front end 25 of 10 this core member being cylindrically formed and projecting through the plate 5. The front portion of the central bore of the body 2 is of larger diameter, as at 8, to provide a space for housing a spring 9 having one 15 end thereof bearing against the corners of the flattened portions 7 of the core member and its opposite end against the bottom wall of the enlarged bore 8. The body portion 2 is also provided with lengthwise extending 20 bores 10, one for each cutter blade, each of these bores having a portion of small diameter at its inner end adjacent the slot 3 for receiving a tripping pin 12 the end of which projects into a V-shaped recess 23 25 formed in the end of the cutter blade, the next adjacent portion of the bore 10 being of larger diameter so as to provide a shoulder against which the head of said pin 12 abuts and also to provide a chamber for 30 housing a spring 13 which exerts its pressure against the head of said pin 12, the opposite end of the spring bearing against a set screw 11, which is threaded into a third portion of said bore 10 of still larger diameter. In the rear face of the body 2 are 35 secured a pair of driving pins 14, the purpose of which will be hereinafter more fully explained.

The shank of the tap is provided with a 40 hub portion 15 having in the front face thereof a central bore adapted to receive a so-called tripping sleeve dog 16, which is provided around its circumference with a groove 17 and at one end with a flange 18 45 adapted to abut against the face of said hub portion 15 and having a central bore of sufficient size to permit passage of the end of the shank 6 of the core member hereinbefore described, the tripping dog 16 being 50 removably secured to said shank portion 6 by means of a pin 19. The hub portion 15 is provided with a pair of threaded radial openings or bores adapted to receive binding screws 20 the ends of which project into the 55 circumferential groove 17 of the tripping sleeve dog and hold the same within the bore of the hub portion 15 against rotation. The flange of the tripping sleeve dog is cut 60 away at opposite sides thereof as shown at 21, Figs. 5 and 7, to leave two portions which act as stop members against which the driving pins 14 of the tap body abut at the proper time for limiting the rotation of the body relatively to the hub portion 15. The 65 front face of the hub portion 15 is also pro-

vided with a pair of radial recesses or slots 22 with which the driving pins 14 coöperate for setting the tap in operative position, as will be hereinafter more fully explained.

The tap is assembled as shown in Figs. 9 70 and 10, that is to say the chasers or cutter blades are placed within the slots 3 of the body and the core member inserted through the central bore of said body 2 with the spring 9 encircling the shank portion 6 75 thereof, the flat portions 7 of the core member being parallel with the backs of the cutters 4. The end plate or disk 5 is then secured to the front face of the body 2 so as to retain the core member in place against 80 the action of the spring 9, whereupon the tripping pins 12 are dropped into the bores 10 of the body, the springs 13 placed within the bores 10, and the set screws 11 screwed into the ends of such bores so as to bear 85 against the ends of the springs 13 and cause them to exert their pressure on the pins 12 to hold the latter firmly in the recesses 23 in the ends of the cutter blades or chasers. The end of the shank portion 6 is then 90 placed in the bore of the tripping sleeve dog 16 and secured therein by means of the pin 19, whereupon the tripping dog is placed within the bore of the hub portion 15 and the binding screws 20 set tightly so as to 95 project into the groove 17 of the tripping member 16 and hold the same against rotation. The parts are thus in the position shown in section in Fig. 10. In other words, the driving pins 14 are withdrawn from the 100 slots 22 in the hub portion 15 and are in contact with the stop members 21 and the flat sides of the portion 7 of the core member are in contact with the backs of the 105 cutters or chasers, so that the cutters are in their withdrawn position and are locked in such position by means of the pins 12 projecting into the V-shaped recesses 23 under pressure of the springs 13.

When it is desired to set the tap into position to thread work which calls for the setting of the tap to its greatest diameter, the body 2 is turned relatively to the hub portion 15, by means of a removable handle 24, until the driving pins 14 are brought 110 into position so that the pressure of the spring 9 will force the body 2 backward so that the pins 14 will enter the recesses 22 in the hub portion 15. At the same time the body has been rotated with relation to the 115 core member so that the corners of the flat portions 7 thereof engage the backs of the chasers or cutters and force them outwardly and hold them in such position, the V-shaped slots 23 in the cutter blades permitting the pins 12 to be forced back against the action of the springs 13 until the ends of such pins are almost withdrawn from 120 said recesses 23, the pressure of the springs 13 against the pins causing the opposite ends 125 130

of the cutters to bear firmly against the disk or plate 5.

In order to adjust the tap to cut any diameter of work ranging from its smallest diameter, to wit, the diameter which it is capable of cutting when the chasers are in their withdrawn position as shown in Figs. 9 and 10, to its largest diameter, or the diameter which it is capable of cutting when the chasers are projected out to their full capacity as shown in Figs. 1 and 11, it is only necessary to loosen the adjusting binding screws 20 which project through the hub 15 into the groove 17 of the sleeve 16 and by means of the slot 26, (see Fig. 2), in the front end of the core member revolve or twist the same in either direction, whereby the relation between corners of the flat portions 7 of the core member with the backs 20 of the chasers or cutters is changed, so that the cutters, as stated, may be set to cut any diameter of work within the limits named above.

The modified form of core member shown in Fig. 12 will permit of a very much greater range of diameters to be threaded. For instance, if the diameter of the work to be threaded is greater than is possible for the tap to reach when the chasers are positioned by a core member having flat sides, the extent to which the cutters may be forced outwardly may be very much increased by providing a core member having some such form as shown in Fig. 12, whereby when the body 2 is rotated relatively to said core member the cutters or chasers will ride or cam on the projecting portions at the corners of this core member.

In the operation of this improved tap, when the tapping operation is finished and the travel of the turret is stopped the tap is automatically released from the work, because of the fact that when the travel of the turret ceases the tap is drawn forward by reason of its engagement with the work, whereby the spring 9 is compressed and the continued rotation of the tap with the work releases the driving pins 14 from the slots 22 in the hub portion 15 and brings the driving pins into contact with the parts 21 of the flange of the tripping sleeve dog, this rotation of the tap having turned it relatively to the core member so that the flat portions 7 of the latter are parallel with the backs of the chasers, whereupon the springs 13 cause the ends of the pins 12 bearing on the side of the slots or recesses 23 in the chasers to force such chasers inwardly, in other words withdraw the same from the work.

It will be understood, of course, that the various details of construction may be more or less varied without departing from the spirit or scope of this improvement. For instance, while I have shown herein a tap comprising only four cutting portions and

a corresponding number of flat surfaces on the core member, I do not desire to confine myself to these details, as the number of cutting members and corresponding flat portions may be increased or decreased as found most desirable in practice.

It will thus be observed that I have provided an improved tap which is adjustable to any diameter within certain limits, and which is automatically released from the work after the tapping operation is completed, and without the necessity of reversing or backing out the threaded piece. It will also be observed that this improved tap can be used for right or left-hand threading without necessitating any change whatever in the mechanism, as it is only necessary to make the chasers either right or left hand and adjusting the core member to suit. It will also be seen that by reason of the construction of the tap access is afforded to all the working parts of the tap so that they can be hardened and ground without materially increasing the cost of manufacture, while the mechanism is so protected when the tap is in use that it is impossible for chips to interfere with the proper operation thereof.

I claim as my invention:

1. A collapsible tap comprising a body, one or more radially shiftable cutters carried thereby, a shank having a hub of no greater diameter than the body, said body and hub being rotatable together and axially shiftable one relatively to the other thereby to release such body and hub for independent rotary movement, and means secured to the hub and extending into the body for shifting the cutters relatively to the body, the diameter of the cutters being greater than any other part of the tap.

2. A collapsible tap comprising a body, one or more radially shiftable cutters carried thereby, a shank having a hub of no greater diameter than the body, said body and hub being rotatable and axially shiftable one relatively to the other, means secured to the hub and extending into the body for shifting the cutters relatively to the body, the diameter of the cutters being greater than any other part of the tap, and means for locking the body and hub together for rotation and adapted to be released on the axial shifting of the body to permit the independent rotation of said body.

3. A collapsible tap comprising a body, one or more radially shiftable cutters carried thereby, a shank having a hub of no greater diameter than the body, said body and hub being rotatable and axially shiftable one relatively to the other, means secured to the hub and extending into the body for shifting the cutters relatively to the body, the diameter of the cutters being greater than any other part of the tap,

means for locking the body and hub together for rotation and adapted to be released on the axial shifting of the body to permit the independent rotation of said body, and means for limiting the rotation of such body.

4. A collapsible tap comprising a body, one or more radially shiftable cutters carried thereby, a shank having a hub of no greater diameter than the body, said body and hub being rotatable and axially shiftable one relatively to the other, means secured to the hub and extending into the body for shifting the cutters relatively to the body, the diameter of the cutters being greater than any other part of the tap, means for locking the body and hub together for rotation and adapted to be released on the axial shifting of the body to permit the independent rotation of said body, and means for limiting the rotation of such body said means adjustable relatively to the hub.

5. A collapsible tap comprising a body, one or more radially shiftable cutters carried thereby, a shank having a hub of no greater diameter than the body, said body and hub being rotatable together and axially shiftable one relatively to the other thereby to release such body and hub for independent rotary movement, means secured to the hub and extending into the body for shifting the cutters relatively to the body, the diameter of the cutters being greater than any other part of the tap, and adjustable means located between the hub and the body for limiting the rotary movement of the body independently of the hub.

6. A collapsible tap comprising a body, one or more radially shiftable cutters carried thereby, a shank having a hub of no greater diameter than the body, said body and hub being rotatable together and axially shiftable one relatively to the other thereby to release such body and hub for independent rotary movement, means secured to the hub and extending into the body for shifting the cutters relatively to the body, the diameter of the cutters being greater than any other part of the tap, and adjustable means located between the hub and the body for limiting the rotary movement of the body independently of the hub, said means comprising a pair of stops and a pair of stop pins.

55. 7. A collapsible tap comprising a body, one or more radially shiftable cutters carried thereby, a shank having a hub of no greater diameter than the body, said body and hub being rotatable together and axially shiftable one relatively to the other thereby to release such body and hub for independent rotary movement, and means secured to the hub and extending into the body and having a plurality of relatively flat corner-

formed faces for shifting the cutters relatively to the body, the diameter of the cutters being greater than any other part of the tap.

8. A collapsible tap comprising a body, one or more radially shiftable cutters carried thereby, a shank having a hub of no greater diameter than the body, said body and hub being rotatable and axially shiftable one relatively to the other, means secured to the hub and extending into the body and having a plurality of relatively flat corner-formed faces for shifting the cutters relatively to the body, the diameter of the cutters being greater than any other part of the tap, means for locking the body and hub together for rotation and adapted to be released on the axial shifting of the body to permit the independent rotation of said body, and means for limiting the rotation of such body, said means adjustable relatively to the hub.

9. A collapsible tap comprising a body, one or more radially shiftable cutters carried thereby, a shank having a hub of no greater diameter than the body, said body and hub being rotatable together and axially shiftable one relatively to the other thereby to release such body and hub for independent rotary movement, a core member secured to the hub and extending into the body and having a plurality of relatively flat corner-formed faces for shifting the cutters relatively to the body, the diameter of the cutters being greater than any other part of the tap, and means for securing the core member in different rotatable positions relatively to the body thereby to change the setting of the cutters.

10. A collapsible tap comprising a body, one or more radially shiftable cutters carried thereby, a shank having a hub of no greater diameter than the body, said body and hub being rotatable together and axially shiftable one relatively to the other thereby to release such body and hub for independent rotary movement, a core member secured to the hub and extending into the body and having a plurality of relatively flat corner-formed faces for shifting the cutters relatively to the body, the diameter of the cutters being greater than any other part of the tap, means for securing the core member in different rotatable positions relatively to the body thereby to change the setting of the cutters, and means for limiting the rotary movement of said body and hub relatively to each other.

11. A collapsible tap comprising a shank having a hub, a core member secured to said hub, a body axially shiftable on and rotatable relatively to said core member and having a plurality of radially shiftable cutters, means carried by said core member and

having a plurality of relatively flat corner-formed faces for shifting the cutters on the rotation of the body relatively to the core member, means for maintaining the body and hub in juxtaposition, means carried between the meeting faces of the hub and body for locking the hub and body together for rotation and adapted to be released on the axial shifting of the body to permit the independent rotation of such body.

12. A collapsible tap comprising a shank having a hub, an adjustable core member secured to said hub, a body axially shiftable on and rotatable relatively to said core member and having a plurality of radially shiftable cutters, means carried by said core member and having a plurality of relatively flat corner-formed faces for shifting the cutters on the rotation of the body relatively to the core member, a spring for maintaining the body and hub in juxtaposition, means carried between the meeting faces of the hub and body for locking the hub and body together for rotation and adapted to be released on the axial shifting of the body to permit the independent rotation of such body.

13. A collapsible tap comprising a shank having a hub, a core member secured to said hub, a body axially shiftable on and rotatable relatively to said core member and having a plurality of radially shiftable cutters, means carried by said core member and having a plurality of relatively flat corner-formed faces for shifting the cutters on the rotation of the body relatively to the core member, a spring for maintaining the body and hub in juxtaposition, means carried between the meeting faces of the hub and body for locking the hub and body together for rotation and adapted to be released on the axial shifting of the body to permit the independent rotation of such body, and means between the meeting faces of said body and hub for stopping the rotation of said body independently of the hub.

14. A collapsible tap comprising a shank having a hub, a core member secured to said hub, a body axially shiftable on said core member and having a plurality of radially shiftable cutters, means carried by said core member and having a plurality of relatively flat corner-formed faces for shifting the cutters on the rotation of the body relatively to the core member, means for maintaining the body and hub in juxtaposition, means carried between the meeting faces of the hub and body for locking the hub and body together for rotation and adapted to be released on the axial shifting of the body to permit the independent rotation of such body, and spring-pressed means carried by the body for locking said cutters within the body.

15. A collapsible tap comprising a shank having a hub, a core member secured to said hub, a body axially shiftable on and rotatable relatively to said core member and having a plurality of radially shiftable cutters, means carried by said core member and having a plurality of relatively flat corner-formed faces for shifting the cutters on the rotation of the body relatively to the core member, means for maintaining the body and hub in juxtaposition, and means carried between the meeting faces of the hub and body for locking the hub and body together for rotation and adapted to be released on the axial shifting of the body to permit the independent rotation of such body and adjustable relatively to the hub to limit the independent rotatable movement of the body.

16. A collapsible tap comprising a shank having a hub, a core member secured to said hub, a body axially shiftable on and rotatable relatively to said core member and having a plurality of radially shiftable cutters, means carried by said core member and having a plurality of corner-formed flat cutter-engaging faces for shifting the cutters on the rotation of the body relatively to the core member, a spring located on said core member and housed within said body for maintaining the body and hub in juxtaposition, means including a pin located between the meeting faces of the hub and body for locking the hub and body together for rotation and adapted to be released on the axial shifting of the body to permit the independent rotation of such body, and means between the meeting faces of said body and hub for stopping the rotation of the body independently of the hub.

17. A collapsible tap comprising a shank having a hub, a core member secured to said hub, a body axially shiftable on and rotatable relatively to said core member and having a plurality of radially shiftable cutters, means carried by said core member and having a plurality of corner-formed flat cutter-engaging faces for shifting the cutters on the rotation of the body relatively to the core member, a spring located on said core member and housed within said body for maintaining the body and hub in juxtaposition, means including a pin located between the meeting faces of the hub and body for locking the hub and body together for rotation and adapted to be released on the axial shifting of the body to permit the independent rotation of such body, and adjustable means between the meeting faces of said body and hub for stopping the rotation of the body independently of the hub.

18. A collapsible tap comprising a shank having a hub, a core member secured to said hub, a body axially shiftable on and ro-

tatable relatively to said core member and having a plurality of radially shiftable cutters, means carried by said core member and having a plurality of corner-formed flat cutter-engaging faces for shifting the cutters on the rotation of the body relatively to the core member, a spring located on said core member and housed within said body for maintaining the body and hub in juxtaposition, means including a pin located between the meeting faces of the hub and body for locking the hub and body together for rotation and adapted to be released on the axial shifting of the body to permit the independent rotation of such body, adjustable means between the meeting faces of said body and hub for stopping the rotation of the body independently of the hub, and spring-pressed means carried by the body for locking the cutters within the body.

19. A collapsible tap comprising a shank having a hub, a core member secured to said hub, a body axially shiftable on and rotatable relatively to said core member and having a plurality of radially shiftable cutters, means carried by said core member and having a plurality of corner-formed flat cutter-engaging faces for shifting the cutters on the rotation of the body relatively to the core member, a spring located on said core member and housed within said body for maintaining the body and hub in juxtaposition, means including a pin located between the meeting faces of the hub and body for locking the hub and body together for rotation and adapted to be released on the axial shifting of the body to permit the independent rotation of such body, adjustable means between the meeting faces of said body and hub for stopping the rotation of the body independently of the hub, and spring-pressed means carried by the body for locking the cutters within the body, the diameter of the cutters being greater than any other part of the tap, said core member and hub being removably connected.

20. A collapsible tap comprising a shank having a hub, a core member secured to said hub, a body axially shiftable on and rotatable relatively to said core member and having a plurality of radially shiftable cutters, means carried by said core member and having a plurality of corner-formed flat cutter-engaging faces for shifting the cutters on the rotation of the body relatively to the core member, a spring located on said core member and housed within said body for maintaining the body and hub in juxtaposition, means including a pin located between the meeting faces of the hub and body for locking the hub and body together for rotation and adapted to be released on the axial shifting of the body to permit the independent rotation of such body, adjustable means between the meeting faces of said body and hub for stopping the rotation of the body independently of the hub, and spring-pressed means carried by the body for locking the cutters within the body, the diameter of the cutters being greater than any other part of the tap.

21. A collapsible tap comprising a shank having a hub, a core member secured to said hub, a body axially shiftable on and rotatable relatively to said core member and having a plurality of radially shiftable cutters, means carried by said core member and having a plurality of corner-formed flat cutter-engaging faces for shifting the cutters on the rotation of the body relatively to the core member, a spring located on said core member and housed within said body for maintaining the body and hub in juxtaposition, means including a pin located between the meeting faces of the hub and body for locking the hub and body together for rotation and adapted to be released on the axial shifting of the body to permit the independent rotation of such body, adjustable means between the meeting faces of said body and hub for stopping the rotation of the body independently of the hub, and spring-pressed means carried by the body for locking the cutters within the body, the diameter of the cutters being greater than any other part of the tap, said core member and hub being removably connected.

the body independently of the hub, and spring-pressed means carried by the body for locking the cutters within the body, said core member and hub being removably connected.

22. A collapsible tap comprising a shank having a hub, a core member secured to said hub, a body axially shiftable on and rotatable relatively to said core member and having a plurality of radially shiftable cutters, means carried by said core member and having a plurality of corner-formed flat faces for shifting the cutters on the rotation of the body relatively to the core member, a spring for maintaining the body and hub in juxtaposition, and means comprising a slot and a pin carried one by the hub and the other by the body adjacent to the meeting faces thereof for locking the hub and body together for rotation and adapted to be released on the axial shifting of the body to permit the independent rotation of such body.

23. A collapsible tap comprising a shank having a hub, a core member secured to said hub, a body axially shiftable on and rotatable relatively to said core member and having a plurality of radially shiftable cutters, means carried by said core member and having a plurality of corner-formed flat faces for shifting the cutters on the rotation of the body relatively to the core member, a spring for maintaining the body and hub in juxtaposition, means comprising a slot and a pin carried one by the hub and the other by the body adjacent to the meeting faces thereof for locking the hub and body together for rotation and adapted to be released on the axial shifting of the body to

permit the independent rotation of such body, and a stop located between the hub and the body for limiting the independent rotation of the body independently of the 5 hub.

24. A collapsible tap comprising a shank having a hub, a core member secured to said hub, a body axially shiftable on and rotatable relatively to said core member and having a plurality of radially shiftable cutters, means carried by said core member and having a plurality of corner-formed flat faces 10 for shifting the cutters on the rotation of the body relatively to the core member, a spring for maintaining the body and hub in juxtaposition, means comprising a slot and a pin carried one by the hub and the other by the body adjacent to the meeting faces thereof for locking the hub and body together for rotation and adapted to be released on the axial shifting of the body to permit the independent rotation of such body, and a stop located between the hub and body for limiting the rotation of the 15 body independently of the hub, said stop being adjustable relatively to the hub.

25. A collapsible tap comprising a shank having a hub, a core member secured to said hub, a body axially shiftable on and rotatable relatively to said core member and having a plurality of radially shiftable cutters, means carried by said core member and having a plurality of corner-formed flat faces for shifting the cutters on the rotation 20 of the body relatively to the core member, a spring housed within said body for maintaining the body and hub in juxtaposition, means comprising a slot and a pin carried one by the hub and the other by the body adjacent to the meeting faces thereof for locking the hub and body together for rotation and adapted to be released on the axial shifting of the body to permit the independent rotation of such body, a stop located 25 between the hub and the body for limiting the rotation of the body independently of the hub, said stop being adjustable relatively to the hub, and spring-pressed means carried by the body for locking said cutters within the body.

26. A collapsible tap comprising a shank having a hub, an adjustable core member secured to said hub, a body axially shiftable on and rotatable relatively to said core member and having a plurality of radially shiftable cutters, means carried by said core member and having a plurality of corner-formed flat faces for shifting the cutters on the rotation of the body relatively to the core member, a spring housed within said body for maintaining the body and hub in juxtaposition, means comprising a slot and a pin carried one by the hub and the other by the body adjacent to the meeting faces thereof 30 for locking the hub and body together for

rotation and adapted to be released on the axial shifting of the body to permit the independent rotation of such body, a stop located between the hub and the body for limiting the rotation of the body independently of the hub, said stop being adjustable relatively to the hub, and spring-pressed means carried by the body for locking said cutters within the body, the diameter of the cutters being greater than any other part of the tap. 70

27. A collapsible tap comprising a shank having a hub of greater diameter than the shank, a body having substantially the same diameter as the hub, a plurality of radially shiftable cutters carried by the body and having greater diameter than the body and hub, a core member secured within the hub and rotatable therewith and projecting into said body and upon which the body is shiftable axially and having a plurality of corner-formed surfaces for engaging the cutters to radially shift them, a spring upon said core member and housed within the body for maintaining the body and the hub in juxtaposition, means carried by the body for holding the cutters therein, means carried by the body and hub for locking said body and hub together for rotation, and means carried between the meeting faces of the body and hub for limiting the rotation of the body independently of the hub and adjustable relatively to the hub. 80 90

28. A collapsible tap comprising a core member having a plurality of relatively flat and cornered surfaces, a body having a plurality of radially shiftable cutters adapted to be radially shifted by said core member into different positions, said body and core being rotatable together and independently one of the other and also axially shiftable relatively to each other, and means for adjusting said parts thereby to permit the core member to hold the cutters in position at their extreme outward or inward positions or in a position therebetween. 100 105

29. A collapsible tap comprising a core member having a plurality of relatively flat and cornered surfaces, a body having a plurality of radially shiftable cutters adapted to be radially shifted by said core member into different positions, said body and core being rotatable together and independently one of the other and also axially shiftable relatively to each other, means for adjusting said parts thereby to permit the core member to hold the cutters in position at their extreme outward or inward positions or in a position therebetween, and means for locking the body and core for rotary movement together. 115 120

30. A collapsible tap comprising a core member having a plurality of relatively flat and cornered surfaces, a body having a plurality of radially shiftable cutters adapted 125 130

to be radially shifted by said core member into different positions, said body and core being rotatable together and independently one of the other and also axially shiftable 5 relatively to each other, means for adjusting said parts thereby to permit the core member to hold the cutters in position at their extreme outward or inward positions or in a position therebetween, means for locking the 10 body and core for rotary movement together, and means for limiting the independent rotary movement of the body and core relatively to each other.

31. A collapsible tap comprising a core 15 member having a plurality of relatively flat and cornered surfaces, a body having a plurality of radially shiftable cutters adapted to be radially shifted by said core member into different positions, said body and core being 20 rotatable together and independently one of the other and also axially shiftable relatively to each other, means for adjusting said parts thereby to permit the core member to hold the cutters in position at their extreme outward or inward positions or in a position 25 therebetween, means for locking the body and core for rotary movement together, and means for limiting the independent rotary movement of the body and core relatively to each other, said cutters having a diameter 30 greater than any other part of the body.

32. A collapsible tap comprising a body, a plurality of removable cutters carried thereby, a shank having a hub provided with a 35 central opening and a pair of radial threaded openings therein, a connecting member passing through said body, a removable sleeve attached to said connecting member and provided with a circumferential groove, 40 said sleeve being adapted to be inserted into the central opening in said hub, a pair of binding screws passing through said threaded openings and coöperating with said groove to secure said sleeve within said hub, 45 said body and shank being rotatable together and independently, and means carried by said connecting member for adjusting said cutters to varying diameters upon rotation of the hub and body relatively to each other.

50 33. A collapsible tap comprising a body having a plurality of radial slots, a removable cutter carried by each of said slots, a core having a cylindrical portion passing through said body and also having flattened 55 portions adapted to support said cutters in said slots, a spring housed within said body and exerting pressure lengthwise of said body and core, a shank to which said cylindrical portion is removably secured whereby 60 the body and shank are rotatable together and independently, and coöperating means carried by said body and shank for limiting the rotation of one independently of the other.

34. A collapsible tap comprising a body, 65 a plurality of removable cutters carried by said body, a shank, coöperating means carried by said body and shank for adjusting said cutters to varying diameters, and means for locking said cutters in any of their adjusted 70 positions, said means comprising spring-actuated pins carried by said body.

35. A collapsible tap comprising a body having a plurality of radial slots, a removable cutter carried by each of said slots and 75 having a recess in one end thereof, a shank, coöperating means carried by said body and shank for reciprocating said cutters within said slots, and spring-actuated pins carried 80 by said body and projecting into said recesses for locking said cutters within said slots.

36. A collapsible tap comprising a body having a plurality of radial slots, a removable cutter carried by each of said slots, a 85 shank, a core having a cylindrical portion passing through said body and removably secured to said shank and also having flattened portions adapted to normally support said cutters in said slots, a spring housed 90 within said body and exerting pressure lengthwise of said body and core whereby said body and shank are held in contact with each other, means for separating said body and shank against the action of said spring 95 and for rotating the body relatively to the shank, and means for limiting such independent rotation and comprising pins carried by one of said members and stops carried by the other.

100 37. A collapsible tap comprising a body having a plurality of radial slots, a removable cutter carried by each of said slots, a shank, a core having a cylindrical portion passing through said body and removably 105 secured to said shank and also having flattened portions within said body adapted to support said cutters in said slots, a spring housed within said body and exerting pressure lengthwise of said body and core whereby said body and shank are normally held in contact with each other, means for separating said body and shank against the action of said spring 110 and for rotating the body relatively to the shank, and means for limiting such independent rotation and comprising pins carried by said body and stop members carried by said shank.

115 38. A collapsible tap comprising a body having a plurality of radial slots open at one 120 end, a removable cutter carried by each of said slots, a removable disk for closing the ends of said slots, a shank, a core having a cylindrical portion passing through said body and removably secured to said shank 125 and also having flattened portions within said body adapted to support said cutters in said slots, a spring housed within said body

and exerting pressure lengthwise of said body and core whereby said body and shank are held in contact with each other, means for separating said body and shank against the action of said spring and for rotating the body relatively to the shank, means for limiting such independent rotation, and means

for locking said cutters within said slots and comprising spring-actuated pins carried by the body.

10

Signed at Cleveland, in the county of Cuyahoga and State of Ohio, this 21st day of March, 1916.

BENJAMIN F. RINDFLEISCH.
